CLAIM

The ornamental design for a case for hearing protection earbuds as shown and described.

DESCRIPTION

1. Case for hearing protection earbuds

1.1 : Perspective

1.2 : Top

1.3 : Bottom

1.4 : Left

1.5 : Right

1.6 : Front

1.7 : Back

FIG. 1.1 is a top, front and right side perspective view of the case for hearing protection earbuds; FIG. 1.2 is a top plan view thereof; and FIG. 1.3 is a bottom plan view thereof; FIG. 1.4 is a left side elevation view thereof; FIG. 1.5 is a right side elevation view thereof; FIG. 1.6 is a front elevation view thereof; FIG. 1.7 is a rear elevation view thereof; the broken lines in the drawings show portions of the case for hearing protection earbuds that form no part of the claimed design.
